UNITED STATES PATENT OFFICE.

JETHRO W. SCROGGIN, OF CORPUS CHRISTI, TEXAS.

SURGICAL AND BATHING APPARATUS.

1,263,611.

Specification of Letters Patent. Patented Apr. 23, 1918.

Application filed November 4, 1916. Serial No. 129,506.

To all whom it may concern:

Be it known that I, JETHRO W. SCROGGIN, a citizen of the United States, and a resident of Corpus Christi, in the county of Nueces and State of Texas, have invented a certain new and useful Improvement in Surgical and Bathing Apparatus, of which the following is a specification.

This invention is an improvement in combined surgical and bathing apparatus, and has for an object to provide a construction wherein a bath tub is supported on a frame and capable of vertical adjustment relative thereto. To this end, use is made of a plurality of standards for end members and side members, the latter of which support the tub, while the former have screw elements mounted therein connected to suitable gear mechanism whereby the operation of the same will result in the raising and lowering of said tub.

Another object is the provision of an operating table mounted above said bath tub and vertically adjustable relative thereto, whereby a patient may be lowered into the tub and lifted therefrom and in order to accomplish this purpose, the table is preferably made in the form of a flexible support operated by novel arrangement of gear mechanism.

The inventive idea involved is capable of receiving a variety of mechanical expressions, some of which are shown in the accompanying drawings wherein,

Figure 1 is a top plan view of one form of the apparatus.

Fig. 2 is a fragmentary detail perspective view of the gear mechanism employed in connection with the invention,

Fig. 3 is a section on the line 3—3 of Fig. 1,

Fig. 4 is a section on the line 4—4 of Fig. 1,

Fig. 5 is a side elevation, partly broken away and shown in sections, of the form shown in Fig. 1,

Fig. 6 is a section on the line 6—6 of Fig. 1,

Fig. 7 is a section on the line 7—7 of Fig. 1,

Fig. 7^a is a top plan, partly in section, of the mechanism shown in Fig. 7,

Fig. 8 is a section on the line 8—8 of Fig. 1,

Fig. 9 is an end view, with parts broken away and shown in sections,

Fig. 10 is a section on the line 10—10 of Fig. 1,

Fig. 11 is a top plan view of another form of the invention,

Fig. 12 is a side elevation thereof,

Fig. 13 is a section on the line 12—12 of Fig. 12,

Fig. 14 is a fragmentary top plan view, with parts broken away and shown in sections of another form of the invention, and

Fig. 15 is a section on the line 15—15 of Fig. 14.

There are shown in the accompanying drawings, what are now believed to be preferred forms of the invention, and by particular reference to Figs. 1 to 10, it will be seen that one form comprises a frame

consisting of a number of standards 20, which are preferably made in three sections 18, 75

19 and 22 adapted to telescope one within the other, the lower sections being hollow

and provided at their lower ends with casters 21, whereby the entire apparatus may

be readily shifted from place to place. The 80

upper section 22 of each standard is preferably in the form of a sleeve member which

receives therein the upper ends of the lower sections, one of said upper ends being internally screw-threaded to receive the screw 85

element 23 which is adapted to be operated, in a manner to appear in the course of the description, to raise and lower the upper

sections 22 in order to adjust the upper portion of the apparatus to the height desired 90

by the operator. The sections 19 are joined by transverse connecting bars 15 the adjacent ends of which are mounted in a

coupling 16 having a screw element 17 therein interposed between said inner ends 95

of the bars, as clearly shown in Fig. 9, so that when said screw element 17 is operated the bars 15 may be forced apart and cause

the sections 19 to bind tightly against the sections 18, and thus assist in maintaining 100

said sections in their respective adjusted positions. The upper end of each sleeve mem-

ber 22 has mounted thereon a gear casing 24, all of which are connected by lower

stationary side members 25 and end members 26, preferably of tubing, said side members being mounted on bosses 27 formed on the casing 24, the opposed portions being oppositely screw-threaded, as shown in Fig. 6. One of the side members 25 and the end members 26 have extending therethrough the rotatable shafts 28 and 29, respectively, the shaft 28 having at each end thereof a beveled gear 30 which meshes with similar gears 31 carried by the upper end of the screw elements 23. The shaft 29 likewise has a beveled gear 32 mounted upon each end thereof, those gears adjacent the shaft 28 meshing with the gears 30 carried by said latter shaft, while the other gears 32 mesh with the beveled gears 31 carried by the upper ends of the other screw elements 23. One of the gear casings 24 shown at the left 20 in Fig. 5, has mounted therein a shiftable crank member 33 having a gear 34 thereon which meshes with an intermediate gear 35 which in turn drives another gear 36 carried by the shaft 28 and arranged contiguous to 25 the gears 30 in said casing. It will thus be seen that when the gear 34 is in mesh with the gear 35 and the crank 33 is rotated in either direction, the shafts 28 and 29 together with the meshing gears will be rotated in such a manner as to either raise or 30 lower the screw elements 23 according to which way said crank is being rotated.

A bath tub 37, preferably made of canvas or other flexible material, is detachably supported upon the side members 25 by means 35 of hooks 38 secured to the upper edge of said tub so that the same may be readily moved, when desired. The lower ends of the standards 20 are connected by braces 39 which 40 may also be detached, if found necessary when removing a patient from a bed onto the apparatus.

A member 40, preferably in the form of a flexible support made of canvas or other 45 suitable material is adapted to be mounted above the bath tub 37 and is vertically adjustable relative thereto, and to this end, there is provided the upper revoluble side members 41 keyed to the shaft 42 and the 50 upper end member 43 surrounding the shaft 44, the side members 41 being journaled in the bearings 45, as shown in Figs. 6 and 7. Each of the side members 41 is provided with a plurality of teeth or prongs 46, which 55 are adapted to be inserted into the material of which the flexible support 40 is made adjacent the longitudinal edges thereof, so as to firmly hold the support in position upon the side members 41. The support 40 60 is wound upon each of the side members 41, as shown in Fig. 4 and said side members are adapted to be rotated in opposite directions in order to permit of the support being lowered or raised, as desired. As shown 65 in Fig. 5, the portion of the support 40 upon

which the head of the patient would rest, is inclined upwardly as indicated at 47 so that if desired, only the feet or legs of the patient resting upon the support need be immersed in the water when the support 70 is lowered into the tub 37. Extending around the bottom of the support 40 at intervals are a plurality of bracing straps 48 provided at each end thereof with hooks 49 which engage over the lower side members 75 25, the same as the hooks 38 of the tub 37. These straps 48 are designed to sustain the weight of the patient when the flexible member 40 is bellied to the limit of its downward adjustment, thereby reinforcing the 80 member 40 when lowered into the tub.

The inner end of the crank member 33 mounted in the gear casing 24 at the left in Fig. 5, is provided with a clutch 50 which meshes with a similar clutch 51 formed upon the adjacent end of the side member 41 and when these clutches are in engagement with each other, the gears 34 will be out of mesh with the gear 35 and the screw elements 23 will not be operated, but upon the turning 90 of the crank 33 in the direction as indicated by the arrows in Fig. 2, the side member 41 having the clutch 51 will also be rotated in a similar direction, as also indicated by the arrow. The side member 41 has a beveled gear 52 mounted thereon which meshes with a similar gear 53 carried by the adjacent end of the member 44, the opposite end of which also has a beveled gear 54, carried thereon which meshes with a similar gear 55 100 carried by the adjacent end of the opposite side member 41, so that the same will be rotated in a reverse direction from the first named side member 41, thus either winding or unwinding the support 40 from said side members. The members 41 may be rotated in the same direction in order to wind the support 40 upon one of them, and to this end, the gear 54 is provided with clutch surface 54' adapted to be engaged by a 105 slideable clutch sleeve 56 connected to an operating handle 56' projecting out of the gear casing 24 so that said portion may be grasped by the operator to shift the sleeve 56 out of mesh with the gear 54 into engagement with the gear 57 whereupon the member 41 which carries said gear 55 will be rotated in the same direction as the opposite member 41.

The speed with which the support 40 may 120 be raised or lowered is automatically controlled by means of a governor. As shown this governor comprises a shaft 60 connected by gears 62 and 63 to one of the longitudinal shafts 42. A brake member 59, 125 splined to the shaft 60 and connected by the weighted governor arms 58 in the manner well understood, is adapted to co-act with a brake member 61 and retard the movement of the support should the same tend to ex- 130

cessive speed. A ratchet wheel 64, secured to one of the shafts, is adapted to be engaged by means of a pawl 65 to hold the support 40 in an adjusted position. Fig. 8.

5 Referring now to Figs. 11 to 13, inclusive, the operating table 66 preferably consists of a plurality of hingedly connected sections 67, each of which is provided upon its opposite longitudinal edges with the supporting arms 68 which extend exteriorly of the upper and lower side members 41 and 25, as shown in Fig. 13, said arms being secured in position by means of the U-shaped fastening elements 69 which embrace said arms and have their ends secured to a base plate 70. Mounted in said plate 70 is a fastening screw 71, the inner end of which is mounted in a yoke member 72 which engages the adjacent side member 25; so that when said screw 71 is turned in one direction, the plate 70 will be drawn outwardly and thus pull the arms 68 tightly against the side member 25 and bind the same in position so that the operating table 66 will be supported 20 in its adjusted position, it being understood that the different sections 67 of said table may be shifted as desired.

From the construction shown in Fig. 12, it will also be apparent that the bath tub 37 30 may be supported upon the side members 25 in the same manner as previously described and shown in Fig. 5.

In Figs. 14 and 15, the flexible support 40 is adapted to be mounted in the ordinary 35 bath tub 73 and for this purpose a plurality of inverted U-shaped members 94 are mounted upon the edges of the tub, and secured in position by means of screw 75 engaging bracing blocks 76. The side members 40 41 are mounted in the top of the members 94 and are operated by the crank and gear mechanism as shown and previously described.

As clearly set forth herein the frame 45 comprises two sets of members and elevating mechanism therefor. One set of members comprises the shafts or side members 25 to which the bath tub 37 and the bracing strips 48 are attached. The other set of members 50 comprises the side members 41 to which the support 40 is attached. Both sets of members may be raised or lowered simultaneously by operating the crank 33 when the gear 34 is in mesh with the gear 35. By 55 throwing the gear 34 out of mesh with the gear 35 and operating the crank 33 the set of members 41 will be operated only to effect independent adjustment of the support 40 to cause it to sag more or less as may be 60 required.

I claim:

1. In apparatus of the character specified a frame embodying two sets of members, elevating mechanism for raising and lowering both sets of members, a support con-

nected with one set of the members, actuating means for operating the support sustaining members to effect independent adjustment of the support, and operating means for the elevating mechanism and the 70 said actuating means including a shiftable element to admit both sets of members being simultaneously raised or lowered or the support sustaining members operated only to adjust the support. 75

2. In apparatus of the character specified, a frame embodying two sets of members, one set of such members being rotatable, elevating mechanism for raising and lowering both sets of members, a flexible support 80 windably connected with the set of rotatable members, and operating means including a shiftable element to admit of simultaneous adjustment of both sets of members or independent rotation of the set of members 85 having the flexible support attached thereto.

3. In apparatus of the character specified, a frame embodying two sets of members, one set of such members being rotatable, elevating mechanism for raising and lowering 90 both sets of members, a flexible support windably connected with the set of rotatable members, sustaining means disposed below the support and attached to the remaining set of members, and operating means including 95 a shiftable element to admit of simultaneous adjustment of both sets of members or independent rotation of the set of members having the flexible support attached thereto. 100

4. In apparatus of the character specified, a frame embodying two sets of members, one set of such members being rotatable, elevating mechanism for raising and lowering both sets of members, a flexible support 105 windably connected with the set of rotatable members, a bath tub arranged below the support and connected to the remaining set of members, and operating means including a shiftable element to admit of simultaneous 110 adjustment of both sets of members or independent rotation of the set of members having the flexible support attached thereto.

5. In apparatus of the character specified, a frame embodying two sets of members, one 115 set of such members being rotatable, elevating mechanism for raising and lowering both sets of members, a flexible support windably connected with the set of rotatable members, a plurality of straps disposed below the flexible support and attached to the remaining set of members, and operating means including a shiftable element to admit of simultaneous adjustment of both sets of members or independent rotation of the 120 set of members having the flexible support attached thereto. 125

6. In apparatus of the character specified, a frame embodying two sets of members, one set of such members being rotatable, a flexi- 130

- ble support windably connected with the set of rotatable members, a plurality of straps disposed below the flexible support and attached to the remaining set of members, a bath tub suspended from the members to which the said straps are attached, and operating means including a shiftable element to admit of simultaneous adjustment of both sets of members and independent rotation of the set of members having the flexible support attached thereto.
7. In apparatus of the character specified, a frame including side members, a flexible support windably connected with the side members, means for rotating one of the members to cause the flexible support to sag, and a plurality of transversely arranged straps to receive and reinforce the support when adjusted to sagging position.
8. In an apparatus of the class described, the combination of a frame including sectional standards, the sections of which have vertical adjustment relative to each other, a bath tub supported by the adjustable sections of said standards and movable therewith, side members forming a part of said frame, and a flexible support carried by said side members and suspended above said tub.
9. In an apparatus of the class described, the combination of a frame including sectional standards the sections of which have vertical adjustment relative to each other, a bath tub supported by the adjustable sections of said standards and movable therewith, side members forming a part of said frame, a flexible support carried by said side members and suspended above said tub, and means for vertically adjusting said flexible support relative to said tub.
10. In an apparatus of the class described, the combination of a frame including sectional standards, the sections of which have vertical adjustment relative to each other, a bath tub supported by the adjustable sections of said standards and movable therewith, rotatable side members carried by the adjustable sections of said standards, and a flexible support adapted to be wound upon and unwound from said side members.
11. In an apparatus of the class described, the combination of a frame including sec-
- tional standards, the sections of which have vertical adjustment relative to each other, a bath tub supported by the adjustable sections of said standards and movable therewith, rotatable side members carried by the adjustable sections of said standards, a flexible support having its longitudinal edges wound upon said side members, and means for rotating said side members for winding and unwinding said support whereby to raise and lower the same.
12. In an apparatus of the class described, the combination of a frame including sectional standards, the sections of which have vertical adjustment relative to each other, a bath tub supported by the adjustable sections of said standards and movable therewith, rotatable side members carried by the adjustable sections of said standards, a flexible support adapted to be wound and unwound from said side members, and a governor for controlling the operation of the last named means.
13. In an apparatus of the class described, the combination of a frame including sectional standards, the sections of which have vertical adjustment relative to each other, a bath tub supported by the adjustable sections of said standards and movable therewith, side members forming a part of said frame, a flexible support carried by said side members and suspended above the tub, and means for alternately adjusting said bath tub and said support vertically.
14. In an apparatus of the class described, the combination of a frame including sectional standards, the sections of which have vertical adjustment relative to each other, a bath tub supported by the adjustable sections of said standards and movable therewith, a flexible support carried by said side members and suspended above the tub, and means including a series of intermeshing gears and a shiftable gear for alternately adjusting said bath tub and said support vertically.

JETHRO W. SCROGGIN.
